(57) **CLAIM**

We claim the ornamental design for a control unit, as shown.

DESCRIPTION

FIG. 1 is a perspective view of a control unit of the present invention;

FIG. 2 is a front plan view of the control unit of the present invention;

FIG. 3 is a side plan view of the control unit of the present invention;

FIG. 4 is a side plan view of the control unit of the present invention;

FIG. 5 is a rear plan view of the control unit of the present invention;

FIG. 6 is a top view of the control unit of the present invention; and,

FIG. 7 is a bottom view of the control unit of the present invention.
